UNITED STATES PATENT OFFICE.

HENRY BUTTRAM, OF MORAN, IOWA.

TOOL FOR REMOVING DRILLINGS FROM BORES.

1,377,665.

Specification of Letters Patent. Patented May 10, 1921.

Application filed July 8, 1920. Serial No. 294,797.

To all whom it may concern:

Be it known that I, HENRY BUTTRAM, a citizen of the United States, residing at Moran, in the county of Dallas and State of Iowa, have invented certain new and useful Improvements in Tools for Removing Drillings from Bores, of which the following is a specification, reference being had to the accompanying drawings.

10 This invention relates to tools for removing drillings from bores and like passages, and has for its object to provide a device of this character whereby the bore may be cleaned.

15 Another object is to provide a device of this character including a sectional handle, said sections being constructed in various or graduating sizes so that the handle may be made as long or short as desired.

20 Another object is to provide a device of this character including a sectional handle adapted to receive a novel form of scoop and drill to remove packed or damped drillings.

25 A still further object of the invention is to provide a device of this character including a scoop for removing drillings from a bore, the ends of said scoop being provided with bits for loosening the drillings, said 30 scoop being rotatable with the bits whereby the side edges of the scoop assist in the cleaning operation, the drillings being removed from the bore upon sliding movement of the scoop.

35 With the above and other objects in view, the invention consists in the improved construction and arrangement of parts to be hereinafter more particularly described, fully claimed and illustrated in the accompanying drawings, in which:—

Figure 1 is a top plan view of a tool constructed in accordance with an embodiment of the invention,

Fig. 2 is a side elevation,

Fig. 3 is an end view.

Referring to the drawings, 5 designates a handle composed of a plurality of sections 6 of graduating lengths, the sections being connected to each other by means of the 50 couplings 7. In this way, the handle may be made as long or as short as desired. In order to remove drillings from a bore, especially in a mine in order to clean the bore for the reception of powder, I provide a 55 novel tool consisting of an elongated semi-

cylindrical scoop 8 having a stem 9 on one end, said stem being threaded for connection to the handle 5 by means of one of the couplings 7. The end 10 of the scoop has its lower portion cut away as at 11 to provide 60 extensions or bits 12. The ends of the bits are tapered, each bit being extended toward the intermediate portion of the scoop and away from each other thereby disposing the bits in circular formation and at the same time 65 permitting unobstructed passage of the drillings into the scoop between said bits. This scoop and bits are intended to remove drillings that have adhered to each other by means of dampness or foreign matter in the 70 bore in which case, the drillings are packed tight within the bore. The bits 12 readily loosen the drillings upon rotation of the handle and the scoop. The drillings are deposited in the scoop and may be readily re- 75 moved from the bore upon retraction of the handle and the scoop.

The scoop is used to readily remove all forms of drillings but is particularly adapted for use in removing packed or damp drillings. This is possible in view of the novel formation of the bits 12. Regardless of the condition of the drillings, they may be readily removed as the bits 12 do not obstruct the entrance of matter to the scoop. 80

From the foregoing it will be readily seen that this invention provides a novel tool for removing drillings from bores and particularly drillings from bores in mines previous to depositing a powder charge in the bore. 90 This device clearly facilitates the work by removing the drillings regardless of their condition with rapidity, without requiring unnecessary strain or labor on the part of the user. 95

What is claimed is:—

1. A scoop of the character described, comprising a body member, one end of said scoop including bits, said bits being disposed adjacent the corners of said end, and 100 having their end portions curved inwardly toward each other in offset relation whereby matter in a passage may be loosened upon rotation of the scoop and deposited into and removed by the scoop upon sliding movement thereof.

2. A scoop of the character described comprising a body member having a pair of diametrically disposed bits, said bits projecting from said end and forming a continuation 110

of the side edges of the scoop, the ends of said bits extending inwardly of the scoop and away from each other.

3. As an article of manufacture, a tool of
5 the character described comprising a scoop
partially closed at one end, the opposite end
thereof having a pair of opposed extensions,
said extensions being disposed adjacent the
10 upper edge of the scoop and projecting be-
yond and in spaced relation to the bottom of
the scoop, the extremities of said extensions
extending in opposite directions.

4. As an article of manufacture, a tool of

the character described comprising a scoop
having a pair of opposed bits projecting 15
from one of the end portions of the sides
of the scoop in spaced relation to the bottom
of the scoop, one of said bits being extended
inwardly and upwardly, the remaining bit
being extended inwardly and downwardly 20
beneath and in spaced relation to the first
mentioned bit, the extremity of each bit pro-
jecting beyond the adjacent bit.

In testimony whereof I hereunto affix my
signature.

HENRY BUTTRAM.
